MAGNETIZED VALVE KEEPER TOOL

George J. Gilbert, Lakeville, Minn.

Application July 30, 1948, Serial No. 41,579

2 Claims. (Cl. 81—3)

1

This invention relates to new and useful improvements and structural refinements in automobile mechanics' tools, and the principal object of the invention is to facilitate application and removal of so-called valve locks or keepers, such as are commonly employed on internal combustion engines.

These keepers, which are quite small, are usually applied or removed while valve springs are abnormally compressed, and since the location of the keepers is poorly accessible, the applying or removing operation is a difficult task, resulting frequently in such mishaps as dropping of the keepers into the engine or losing them on the ground.

The instant invention, therefore, contemplates to eliminate these disadvantages; this being achieved by the provision of a valve keeper installing and removing tool wherein a pair of coacting jaws, possessing magnetic characteristics, are employed for firmly and securely holding the valve keepers until such time as the latter are fully installed in or fully removed from the engine.

An important feature of the invention resides in providing the magnetized jaws with a non-magnetic handle, whereby the tool is prevented to a great extent from attracting or being attracted to various components of the engine which are not being worked on.

An additional feature of the invention lies in universal mounting of the handle, whereby the tool may be conveniently and effectively employed in poorly accessible locations.

A still further feature of the invention resides in the provision of a modified handle structure for the magnetic jaws; this modified handle structure being of a resilient character, so that the jaws are normally separated for reception of valve keepers therebetween.

A still further feature of the invention lies in the provision of clamps on the magnetic jaws, whereby the latter may be clamped in position on two fingers of the user's hand in order to facilitate maximum dexterity.

With the above more important objects and features in view and such other objects and features as may become apparent as this specification proceeds, the invention consists essentially of the arrangement and construction of parts as illustrated in the accompanying drawings, in which:

Figure 1 is a perspective view of the invention, showing the jaw forming block as being separated from its socket and handle;

2

Figure 2 is a side elevational view of the invention in its assembled form;

Figure 3 is a cross sectional view, taken substantially in the plane of the line 3—3 in Figure 2;

Figure 4 is a top plan view of the subject shown in Figure 2;

Figure 5 is a cross sectional view, taken substantially in the plane of the line 5—5 in Figure 4;

Figure 6 is a side elevational view showing a modified embodiment of the socket and handle structure;

Figure 7 is a cross sectional view, taken substantially in the plane of the line 7—7 in Figure 6;

Figure 8 is a perspective view of a further modified embodiment of the invention;

Figure 9 is a fragmentary side elevational view of the subject shown in Figure 8;

Figure 10 is a cross sectional view, corresponding to the elevational view shown in Figure 10, but illustrating the jaws as being brought together;

Figure 11 is a fragmentary cross sectional view, taken substantially in the plane of the line 11—11 in Figure 8 and illustrating the embodiment shown in Figures 8, 9 and 10 as being employed in a somewhat different manner; and

Figure 12 is a perspective view of a still further modified embodiment of the invention.

Like characters of reference are employed to designate like parts in the specification and throughout the several views.

Referring now to the accompanying drawings in detail, more particularly to Figures 1—5 inclusively, this invention consists of a valve keeper installing and removing tool designated generally by the reference character 20, the same embodying in its construction a block 22 possessing magnetic characteristics and provided with a substantially V-shaped recess 24 defining a pair of coacting jaws 26 at the sides of the recess, substantially as shown.

It is to be noted that the jaws 26 have mutually opposed surfaces 28 which diverge not only outwardly as is best shown in Figure 2, but also longitudinally, as illustrated in Figure 4. Moreover, the base or apex of the V-shaped recess 24 is relieved so as to form a longitudinal channel 30, whereby machining of the surfaces 28 is facilitated.

It should be also noted that the jaws 26 are provided at one end with inwardly projecting

flanges 32, best shown in the accompanying Figures 1, 3, 4 and 5.

The base portion of the block 22 is receivable in a complementarily configurated socket 34, the latter preferably being formed from non-magnetic material and being equipped with a convenient handle portion 36. It should be also noted that the socket 34 is provided at the opposite ends thereof with suitable notches 38 in register with the channel 30 when the block 22 is in position in the socket 34, substantially as shown.

When the invention is placed in use, such as for example, when installing valve keepers, the keepers are simply applied to the surfaces 28 of the magnetized jaws 26 as indicated at 40 in Figure 2, the two keepers preferably being disposed in a juxtaposed relation, so that when the tool, together with the keepers is advanced toward the valve stem 42, pressure of the valve stem against the abutting longitudinal edges of the keepers will cause them to envelop the valve stem, so that installation thereof will be readily effected. It is to be particularly noted that the jaws 26, by virtue of their magnetic characteristics, will firmly retain the keepers in position until such time as they are fully applied to the valve stem, whereby misplacement and loss of the keepers will be prevented.

The channel 30 in the block 22 as well as the notches 38 in the socket 34 provide sufficient clearance for the valve stem 42 after the keepers are applied, as will be clearly understood. It should be also explained that inasmuch as the keepers 40 are usually of a tapered configuration, the surfaces 28 are longitudinally divergent, so that they may flatly engage the outer surfaces of the keepers.

Moreover, since the surfaces 28 are inclined in two directions, vertically and longitudinally, the longitudinal inclination will enable the surfaces to conform to the usual taper of the valve keepers as above noted, while the vertical inclination will facilitate accommodation of valve keepers of different sizes, over and beyond the range which is encompassed by the taper in the longitudinal direction. The longitudinal channel 30 is intended to facilitate machining of the surfaces 28 by permitting the machining tool to reach the lower edge portions of those surfaces without obstruction.

When the keepers are being removed from the valve stem, the tool is simply applied in position adjacent the stem and the keepers are manually separated from the stem, while the attraction of the jaws 26 draws the keepers against the surfaces 28, thus preventing their possible loss.

It is to be noted that the flanges 32 will effectively function as rests or stops for preventing the keepers from sliding on the surfaces 28.

Referring now to the modified embodiments of the invention illustrated in Figures 6 and 7, these illustrate a modified embodiment of the aforementioned socket 34 and handle 36, the modified structure being illustrated by the reference character 44 which designates the socket, while the reference character 46 indicates the handle.

In this embodiment, however, the socket 44 is provided at the base thereof with a ball 48 which is adjustably receivable in a socket member 50 provided at one end of the handle 46, a complementary socket half member 52 being secured in position on the handle 46 by means of a suitable screw 54, so that the two socket half members coact in enveloping the ball 48, as will be clearly understood. By virtue of this socket

construction, the handle 46 may be moved in all directions with respect to the socket 44, thereby facilitating the use of the tool in poorly accessible locations. Needless to say, the socket 44 is intended to receive a jaw forming block, similar to the aforementioned block 22.

Referring now to the accompanying Figures 8, 9, 10 and 11, these illustrate a further modified embodiment of the invention designated generally by the reference character 56, wherein the jaws 58 are formed separately or individually rather than "inblock," and are suitably secured, as by welding or the like, to the free end portions 60 of the arms of a resilient handle 62, configurated substantially as shown.

The resiliency of the handle 62 is such as to normally maintain the jaws 58 in a separated position, so that application of the tool to the valve stem is readily facilitated. Needless to say, by simply compressing the arms of the handle 62, the jaws 58 may be brought in engagement with the keepers, or alternatively, the keepers indicated at 64 in Figure 9, may be brought toward the valve stem 66.

The accompanying Figure 11 illustrates a set of two pairs of valve keepers 68 retained in a juxtaposed relation in the jaws 58, this being a modified use of the aforementioned tool 56, wherein the two valve keepers 68 are applied to the valve stem in much the same manner as when the tool 20 is employed. If desired, grooved inserts 70 of resilient material may be provided in the jaws 58 for preventing the keepers in each jaw from collapsing, such inserts being applicable to the various embodiments of the invention, as exemplified at 72, 74 and 76 in Figures 2, 6 and 8 respectively.

It is to be noted that when two valve keepers are in juxtaposed relation, the substantially semi-cylindrical configuration thereof would tend to collapse them when applied to a valve stem by engaging their inner contiguous edges with the stem, as for example, in Figure 2. The resilient inserts 70 are intended to properly support the keepers against such collapsing, not only by the particular configuration of the keepers, but also by the inherent resiliency of the material from which the keepers are formed which discourages sliding or slipping of the keepers thereon.

Referring now to the accompanying Figure 12, this illustrates a still further modified embodiment of the invention designated by the reference character 78, wherein a pair of independent coacting jaws 80, similar to the aforementioned jaws 58, are provided with resilient fingers 82 constituting what may be referred to as clamps, whereby the jaws may be conveniently attached to the fingers of the user's hand. In this manner, provision of a socket and a handle for holding the jaws is obviated, and it will be found that the jaws may be manipulated by the user's fingers with considerable dexterity, as will be clearly appreciated.

It is believed that the advantages and use of the invention will be readily understood from the foregoing disclosure, and accordingly, further description thereof at this point is deemed unnecessary.

While in the foregoing there has been shown and described a preferred embodiment of this invention it is to be understood that minor changes in the details of construction and arrangement of parts may be resorted to without departing from the spirit and scope of the invention as claimed.

Having described the invention, what is claimed as new is:

1. A tool for installing valve keepers comprising a U-shaped member having magnetic characteristics, said member including a web portion and leg portions, the outer ends of said leg portions having flat surfaces diverging outwardly relative to a plane disposed medially between said leg portions and also diverging relative to the longitudinal axis of said member, inwardly projecting flanges on said surfaces adjacent the longitudinally divergent end thereof, said flanges constituting keeper rests.

2. A tool for installing valve keepers comprising a U-shaped member having magnetic characteristics, said member including a web portion and leg portions, the outer ends of said leg portions having flat surfaces diverging outwardly relative to a plane disposed medially between said leg portions and also diverging relative to the longitudinal axis of said member, inwardly projecting flanges on said surfaces adjacent the

5

longitudinally divergent end thereof, said flanges constituting keeper rests, said web portion having a recess therein, and said flat surfaces being contiguous with the side walls of said recess.

GEORGE J. GILBERT.
